UNITED STATES PATENT OFFICE.

SVEND M. MEYER, OF BROOKLYN, NEW YORK, ASSIGNOR OF ONE-HALF TO HERMAN L. RINGELMANN, OF BROOKLYN, NEW YORK.

SOLDERING IRON.

Application filed November 18, 1925. Serial No. 69,827.

Soldering irons consist essentially of a large body of copper capable of holding a great amount of heat and having a pointed "tip" either integral with the body or separate therefrom whereby the heat of the body of the "iron" can be applied to a limited point of the work to effect the soldering. Such copper bodies while having the advantages of great specific heat and conductivity combined with a fair degree of resistance to oxidation at low temperature, still have some serious drawbacks. Chief among these is the tendency when heated to form obnoxious gases, which are not only injurious to humans, but act deleteriously on the surfaces at the tip of the iron, even when the said tip is not directly in the fire, dulling their brightness, so as to render them less efficient in "taking" the tinning, without which successful soldering is impossible. It is therefore common practice to continually renew the brightness of the tip by filing or by other abrasive means.

In my invention I make the heat absorbing body of aluminum or an alloy of aluminum while retaining the copper of the tip. The body may be all aluminum or be provided with a copper core. Such an iron even when heated to redness produces no fumes, so that the obnoxious effects produced by the copper irons is obviated. Such aluminum irons possess the further advantage of being almost three times lighter than copper irons of equal heat capacity. The copper tips are secured on the aluminum body by a tongue and recess construction whereby a rapid flow of heat from the body to the tip is secured and the tip is further secured to the body by a wedge key that aids in the conduction of heat while presenting an easy means of attaching or detaching the tip without other aid than a light tap. Removable copper tips of copper soldering tools are liable to become permanently attached to the copper bodies either by oxidation or soldering whereas it is desirable to have a construction that will allow easy detachment when cold. With an aluminum body such attachment of tip to body does not occur. My invention is equally applicable to cauterizing instruments or the like.

In the accompanying drawings in which is shown an embodiment of my invention:—

Figure 1 represents a side view partially in section of the complete iron;

Figure 2 is a side view of a special form of tip;

Figure 3 is a side view and partial section of a cauterizing tool.

The main body of the soldering tool is shown at 1. This may be in the shape of a cylinder or a prism. This body portion I make of aluminum or an alloy of aluminum and some strengthening metal such as antimony and copper, such strengthening component being always a small proportion of the total, just enough in fact, to give the desired degree of hardness without materially increasing the weight.

At 2 is shown a core of copper which is cast in the aluminum. The core is provided with radial vanes 3. This copper core is so embedded in the aluminum as to be nowhere exposed to the atmosphere. It serves together with its vanes to equalize the distribution of heat throughout the length of the aluminum body. This it does by virtue of its superior conductivity for heat. At

one end of the body 1, I form a recess 4, preferably of cylindrical shape, which recess is adapted to form the socket for a cylindrical shank 5 of a copper tip 6. The shank 5 is intended to have a snug fit in the recessed socket 4 and is additionally held therein by means of a transverse key 7 passing through slots in the tip and the body. This key 7 I prefer to make of some metal having a great expansion with heat such as cobalt alloys, so that when heat is applied to the body and from thence to the tip and key, the expansion of the tip and the still greater expansion of the key will bring the tip and key to firm contact with the aluminum body to not only hold the tip securely in place, but form a more perfect joint for the conduction of heat. At the other end or base of the body portion 1, a brass or other suitable metallic ring 8 is screwed onto the body and in a counterbored recess in said

rim I secure a disk of refractory material 9, such for example, as any one of the more refractory asbestos compositions. The upper side of this disk is recessed for the reception of a metallic washer 10. A screw 11 passes through the washer 10 and disk 9 and a nut 12 secures the same securely in place by clamping the washer 10 and disk 9 between the nut and the head of the screw. A suitable handle 13 of wood or other material having poor conductivity is provided

with a metallic bushing 14, which is adapted to screw on to the part 11 until the handle, at its inner end, comes in contact with the disk 9. The disk 9 may be held in the rim 8, by having a thin edge of the ring 15, spun over the edge of the disk in the manner shown. It will be seen that an air space is left between the body 1 and the handle portion so that the handle remains fairly well 10 heat insulated from the body, the only contacts being through the insulating disk 9. In use only the aluminum body portion will be placed in the fire or the gas flame and the handle 13 may be removed during the 15 heating of the body. During this heating there will be no fumes given off from the body as would be the case were the body made of copper and the tip 6 being covered with tin will remain untarnished. The body 20 1 will remain also bright, clean and free from oxide. In Figure 2, I have shown a tip having a side point 6 as an example of one of the many forms that the tip may be made to have, all of which different forms 25 would be made interchangeable with each other.

In Figure 3 I have shown a cauterizing tool or instrument. Here the shank 5 of copper for example, has a silver extension 16, the pointed end of which 17, has a gold or platinum coating 18. Such a cauterizing tool may, in many instances, have advantages over an electrical instrument, as heat is more universally accessible than electricity. While I have shown a particular embodiment of my invention, in Figure 1, I do not wish to be limited to the specific forms shown therein as many modifications will occur to those skilled in the art. Thus the handle may be permanently attached to a 40 long rod extending from the body, or the tips may be securable on the body in many other ways than that shown. It is evident also that the invention may be equally applicable to electric irons. 45

I claim:—

A heating tool of the character described comprising a body portion chiefly of aluminum, a central core therein of copper with vanes extending laterally into the aluminum body and a copper tip. 50
